ELECTRICAL SOCKET BOARD

Ronald J. Portugal, 52 Susan Lane,
North Haven, Conn. 06473

Continuation-in-part of design application Ser. No.
413,919, Nov. 8, 1973. This application Mar. 27,
1975, Ser. No. 562,593

Term of patent 14 years

Int. Cl. D13—03

U.S. Cl. D26—1 A

Fig. 1.

Fig. 2.

Fig. 3.

Fig. 5-FIG. 1 is a top plan view of an electrical socket board showing my new design;

FIG. 2 is a side elevational view looking from the right of FIG. 1;

FIG. 3 is an end view looking from the bottom of FIG. 1;

FIG. 4 is an end view looking from the top of FIG. 1;

FIG. 5 is a bottom view of the electrical socket board of FIG. 1; and

FIG. 6 is a side elevational view looking from the right of FIG. 5.

The sockets are partially shown for convenience of illustration, it being understood that the sockets are uniformly continuous on the areas on which they are indicated.

The application is a divisional continuation-in-part of design application Ser. No. 413,919, filed Nov. 8, 1973, for electrical socket.

I claim:

The ornamental design for an electrical socket board, substantially as shown and described.
